AUTOGRAPHIC REGISTER

Harry J. Waechter, Mount Healthy, Ohio, assignor to Paul Benninghofen and Fritz G. Diesbach, trustees, Hamilton, Ohio

Application October 13, 1937, Serial No. 168,782

6 Claims. (Cl. 282—12)

This invention relates to improvements in autographic registers or manifolding machines, particularly for manifolding and dispensing shipping or sales bills and the like. The shipping or sales bills dispensed by these machines are incorporated in continuous strips of paper either wound on reels or folded into packets and dispensed in definite measured proportions corresponding to the length of the individual shipping bill or sales slip. Thereafter the bills or strips are severed from the strips. These continuous strips of paper, or continuous form stationery, are fed from a supply compartment upon and over a writing table or platen.

15 It has been the custom to feed the strips by the engagement of pins, in the machine, with filing apertures or holes, located in the spacing between the forms and adjacent the tear-off lines established across the strips. These apertures have 20 been utilized in the operation of withdrawing the strips in lengths representing the full length of each printed form. Moreover, they have been utilized in the operation of aligning, registering, and holding the printed forms of the several strips 25 upon the writing table for making the entries.

It has been the object of the present inventor to provide a device of this character which will deliver upon a writing table or platen and dispense the continuous strip form of stationery in 30 packet form without utilizing the filing holes in the paper, that is without employing any means cooperating with these filing holes in the delivery or issuance of the paper from the packet to the writing table and from the writing table 35 to a tear-off position.

It has been a further object of this inventor to provide a device of this character which is extremely compact and simple, in fact, of such size as to be more portable than has heretofore 40 been possible. Furthermore, it has been the further object to provide a device of this character in which the sales forms are held securely upon the platen during the writing operation and wherein a convenient hand rest is provided without the addition of parts or enlargement of the 45 device.

In the past, in the pin feed type of machine, the accuracy of feed has been entirely dependent upon the proper engagement of the feeding and 50 aligning pins with the apertures. The present inventor has accomplished his objects in the provision of a machine in which the disposition of each successive set of forms upon the table or platen and the delivery of the forms from the 55 table are always accurate, an accomplishment

resulting solely from the operation of swinging the platens and reversing their superposed position. The arrangement is such that the manual operations of lifting the platen upon which the writing has taken place and of dropping the 5 platen, which has covered the writing table, into position beneath the writing platen, cause the forms to lie in perfect registry. Thereafter, the set of forms, which have been filled in, are held for tear-off along the lines of severance, i. e. the 10 fold lines, which lie directly against the edge of the platen about which the strips have been turned.

In the present invention the carbon may be inserted between the strips in any convenient 15 manner. It is preferable to use the type of packet wherein the carbon strips are incorporated as a part of the packet.

Other objects and certain advantages will be more fully apparent from a description of the 20 accompanying drawings, in which:

Figure 1 is a perspective view of the improved sales slip dispensing device, showing the device in position for filling out a sales slip.

Figure 2 is a perspective view illustrating the 25 device in the stage of operation for advancing the paper to deliver a set of forms therefrom.

Figure 3 is a perspective view illustrating the 30 operation of tearing off the filled out delivered sales slips.

Figure 4 is a perspective view similar to Figure 1, illustrating the platens reversed as to position.

Figure 5 is a longitudinal sectional view taken 35 on line 5—5, Figure 1.

Figure 6 is a cross sectional view taken on lines 6—6, Figure 1.

Figure 7 is a perspective view of the superimposed strips of sales slips illustrating the arrangement of the printing thereon and the stacking.

The disclosed embodiment of the invention provides a compartment for the pack. The superimposed strips of paper are folded in zig-zag form into a packet upon the lines of severance. The delivery mechanism is a part of the writing platen structure. Superimposed platens are provided 45 hinged at opposite ends of the compartment. In the initial stage, the device is loaded by lifting one section or set of sales slips of the packet and dropping one of the platens beneath the same. The device is then ready for use. For coverage 50 purposes the other platen may be swung down upon the superimposed set of sales slips.

Thus, it may be said that the device consists in 55 its entirety of a compartment having a pair of platens at its open upper side, the platens hinged

or folded at opposite ends. The paper is printed upon reverse sides considering the successive sections of the superimposed strips. In other words, the sections are printed on alternate sides.

5 Referring to the drawings, the compartment is indicated at 10. It provides a bottom, 11, sides, 12, 12, and ends, 13, 13, and is closed at its upper side by the overlapping platens, 14, 15. For the purpose of mounting the platens for swinging 10 movement, hinge ears, 16, are provided, one at each corner of the device, forming a continuation of the side walls thereof in each instance. The platens incorporate pivot studs or hinges, 17, projecting laterally from opposite corners and 15 engaged in slots, 18, in the hinge ears. The slots are vertically disposed. The platens are provided with laterally extended grip portions, 19, at their outer free or swinging ends. These portions project beyond the lines of the compartment for 20 convenient engagement when the platen is to be lifted. The sides of the compartment are notched out, as at 20, to receive the extensions, 19.

25 The strips of manifolding paper, 21, are disclosed in triplicate in the present case and include carbon strips as a part of the packet. The machine is loaded by lifting both platens and engaging the endmost set of forms upon the upper 30 face of one of the platens. The fold then engages over the end of the platen as shown in Fig. 1. This platen is then swung on its hinges or allowed to drop down to a position of support on the compartment, where it serves as a firm writing 35 table. The other platen, 15, in the drawings, then functions as a hand rest or as a cover.

40 After the form has been filled out, further feed of the strips and delivery of the filled out forms is a simple procedure. The operator raises the platen 14, which has been serving as a writing table, enough that it clears the other platen, 15, which then drops into position, and then he drops the platen 14. The filled out forms are now 45 lying on top of the platen 14, free of mechanism, and they can be torn off along the forward edge, 22, of this platen. The next set of forms is left between the platens for future use.

50 The top platen, which is drawn back when the form is being written upon, functions as a hand rest as will be apparent from the drawings. This is particularly advantageous when the writing is 55 being done toward the lower end of the forms. As will be apparent from Figures 1 and 5, the paper is held securely upon the writing platen against forward movement due to the fact that it is hooked around the end edge of the platen or around that edge against which the forms are subsequently torn from the strips, see Figure 4.

60 The edge, 22, of both of the platens or leaves, is tapered or provided with a knife edge to fit the crotch which is formed by a paper fold serving to align the forms upon the platen and to hold the same against translation over the edge, as translation over the edge would destroy the registration of a set of forms for manifolding. The 65 knife or sharp edge also is of advantage for a form tear-off operation.

Having described my invention, I claim:

70 1. A portable manifolding device comprising a compartment adapted to receive a strip of printed forms, platens adapted to be disposed in superimposed relationship across the open side of the compartment, and said compartment in-

cluding hinge portions at each corner provided with vertical slots, said platens respectively including hinge pivots at opposite ends engaging in the slots, said platens adapted to be swung clear of each other and interchangeable as to 5 superimposition.

2. A sales slip package comprising a shallow receptacle having an open top, a pair of writing platens respectively hinged at opposite ends of said receptacle and superimposed in closed position 10 on top of the receptacle, and continuous strips of printed forms having adjacent forms printed on opposite sides, said strips folded into a zig-zag pack at the lines of separation of the forms, and the writing platens engaged into the 15 zig-zag pack from opposite sides thereof.

3. A sales slip dispensing package comprising a receptacle having an open top, a continuous strip of sales forms folded upon the lines of separation of the forms to constitute a zig-zag pack, 20 said pack disposed in said receptacle, writing platens respectively hinged at the opposite ends of said receptacle and lying in superimposed relationship for closing the top of the receptacle, means for sustaining said writing platens in a 25 plane at the top of the receptacle and said writing platens interleaved with the zig-zag folded strips from opposite sides thereof.

4. A sales slip dispensing package comprising a receptacle having an open top, a continuous 30 strip of sales forms folded upon the lines of separation of the forms to constitute a zig-zag pack, said pack disposed in said receptacle, writing platens respectively hinged at the opposite 35 ends of said receptacle and lying in superimposed relationship for closing the top of the receptacle, said strip of sales forms having adjacent forms printed on opposite sides of the strip, means for sustaining said writing platens in a plane at the top of the receptacle, and said writing platens interleaved with the zig-zag folded strips from 40 opposite sides thereof.

5. A portable sales slip dispensing device comprising a compartment having an open top and adapted to receive a continuous strip of printed forms, which strip is zig-zag folded into packet form on the respective lines of separation of the folds, platens respectively hinged at opposite ends of the compartment, said platens when in closed 45 position extending substantially entirely across the open top of the compartment, and each providing a tear-off edge adapted to engage the adjacent line of separation of the forms disposed above and below the same.

6. A portable sales slip dispensing device comprising a compartment having an open top and adapted to receive a continuous strip of the 55 printed forms, which strip is zig-zag folded into packet form on the respective lines of separation of the folds, platens respectively hinged at opposite ends of the compartment, said platens when in closed position extending substantially entirely across the open top of the compartment, each 60 of said platens providing an edge adapted to engage the adjacent line of fold of the forms disposed above and below the same and constituting an edge against which the uppermost form may be torn from the packet, and extensions on said 65 platens engageable with the sides of the compartment for supporting the platens when in position across the top of the compartment.

HARRY J. WAECHTER.
